UNITED STATES PATENT OFFICE.

MARSHALL L. SHEPHERD, OF MONTGOMERY, ALABAMA, ASSIGNEE TO SHEPHERD AUTOMATIC SWITCH CO., OF MONTGOMERY, ALABAMA.

RAILWAY-SWITCH MECHANISM.

1,070,297.

Specification of Letters Patent. Patented Aug. 12, 1913.

Application filed February 18, 1913. Serial No. 749,151.

To all whom it may concern:

Be it known that I, MARSHALL L. SHEPHERD, a citizen of the United States, residing at Montgomery, in the county of Montgomery and State of Alabama, have invented new and useful Improvements in Railway-Switch Mechanism, of which the following is a specification.

This invention relates to railway switch mechanism for controlling the passage of rolling stock from a main track to a branch track or siding, and vice versa.

The primary object of the invention is to provide a positive and reliable type of switch mechanism adapted to be automatically operated by the rolling stock and locked and guarded, in normal or switch-closing position, against surreptitious or accidental adjustment.

20 A further object of the invention is to provide a switch mechanism which is adapted to be automatically operated by the rolling stock from either the main or branch line and to lock the open switch rails against 25 accidental closing and insure their positive control by the rolling stock until the latter has passed from one track to the other.

A still further object of the invention is to provide a switch mechanism which will 30 positively close after actuation and the passage of a train from one track to the other and lock the switch rails in normal or closed position so as to obviate the liability of accidents to following trains, while permitting 35 through trains on the main line to travel over the switch point at high speed without liability of derangement of the switch mechanism.

A still further object of the invention is 40 to provide a switch mechanism which cannot be left open, which obviates the well known objections to switches of the kind in common use, which is operable automatically by means under control of the driver 45 or engineer of a car or locomotive and may also be operated in an authorized manner by hand when occasion requires and in conjunction with a suitable switch stand and signal, and which affords a maximum safety 50 guard against accidents to the traveling public.

A still further object of the invention is to provide a hand switch throwing mechanism which, after actuation, will be auto-

55 matically returned to and locked in normal position, thus avoiding all liability of the switch being left open through negligence on the part of an employee.

A still further object of the invention is to provide a switch mechanism which permits actuation of the switch point through 60 any of the switch throwing agencies mentioned without interference from the others, and in which provision is made for controlling a single switch locking device by and 65 from any of the switch throwing devices.

A still further object of the invention is to provide a switch mechanism which will 70 adjust itself to, or compensate for any loose play of the parts which may occur from wear or any slight variation from the normal in the distance between the track rails due to spreading or to contraction and expansion of the parts.

With these and other objects in view, the 75 invention consists of the features of construction, combination and arrangement of parts, hereinafter fully described and claimed, reference being had to the accompanying drawings, in which:

Figure 1 is a top plan view of the rails and switch mechanism at a switch point, showing the switch rails locked in normal position for travel on the main line. Fig. 2 is a similar view of the switch mechanism 85 on an enlarged scale and with the cover plate removed and parts appearing in section. Fig. 3 is a view similar to Fig. 2 showing the switch thrown open for travel between the main and branch lines. Fig. 4 is a vertical transverse section on line 4—4 of Fig. 2. Fig. 5 is a vertical transverse section on line 5—5 of Fig. 3. Figs. 6, 7 and 8 are detail plan views showing the action in releasing the switch locking device from the 95 main and branch line automatic switch throwing devices and the manual switch throwing device, respectively. Fig. 9 is a vertical transverse section on the line 9—9 of Fig. 2. Fig. 10 is a vertical transverse section on the line 10—10 of Fig. 1. Figs. 11 and 12 are detail views illustrating the action of the lock releasing device in the main line. Fig. 13 is a vertical longitudinal section through the main line switch throwing device. Fig. 14 is a vertical transverse section of the same, showing also the actuating device carried by the locomotive. Fig.

15 is a sectional plan view of the switch lock releasing means controlled by the hand switch. Fig. 16 is a perspective view of the switch locking device. Fig. 17 is a similar 5 view of the bell-crank trip lever forming part of the lock releasing means in the main line. Fig. 18 is a view of the locking means for holding the hand switch lever closed. Fig. 19 is a detail view showing a modified 10 form of connection between the switch bar and the rock shaft of the main line switch throwing mechanism.

Referring to the drawings, 1 and 2 designate 15 the main line rails, 3 and 4 the branch line or siding rails, and 5 and 6 the switch rails, constituting the switch point, which switch rails are coupled for movement in unison by the switch bar 7, and may also be connected in practice by suitable tie rods in 20 the usual manner.

Arranged between the tracks of the main line, in the main line approach to the switch, is a casing 8 bolted or otherwise firmly secured to the ties and having at one side a 25 longitudinal slot 9. In this casing is revolvably mounted a switch throwing member 10 comprising a drum or roller provided with a spiral groove 11, having reversely extending end portions 12 and 13 and a 30 substantially straight intermediate portion 14. The spiral groove is adapted to receive a friction roller 15 upon the laterally bent lower end of a switch actuating or trip device 16 suitably mounted in practice upon a 35 car or locomotive and adapted to be projected and retracted by suitable operating means. The laterally bent end of the actuating device 16 is also provided with a friction roller 17 to travel in the slot 9, and 40 arranged parallel with the slotted side of the casing is a guard plate 18 forming a guideway for the travel of the actuating device and acting to prevent the introduction of a tool in an attempt to tamper with the drum 45 or throw the switch. Hence the drum can only be turned by a proper type of actuating device under the power of the locomotive or car on which it is mounted.

The parts of the switch throwing device 50 in the main line, above described, are and may be substantially the same as disclosed in my prior application #651738 filed September 28, 1911.

Projecting forwardly from the drum is a 55 shaft 19 journaled in one or more suitable bearings 20 and carrying adjustable collars 21 and 22, each secured thereto by a set screw 23. The collar 21 is provided with a crank arm 24 to which is pivotally connected 60 a latch releasing dog or member 25, comprising a bar having a beveled end portion 26 formed with a trip shoulder 27 and a guide shoulder 28. The dog 25 and parts of 65 the latch mechanism hereinafter described are mounted upon a suitable base 29, on

which the dog is free to slide and have tilting motion, and fixed to this base is a guide and trip block 30 cut away to provide a guide slot 31, a beveled end 32 and a slot 33 communicating with the top of the slot 31 and opening through said beveled end 32. Extending into the slot 31 is one end 34 of a bell crank latch releasing lever 35 having at its opposite end a finger 36 slidably and pivotally engaging a notch 37 in one end of 70 a pivoted latch or locking device 38, which end of said latch or locking device is provided with a locking finger 39 for engagement with either one of a pair of locking recesses or notches 40 and 41 in the switch bar 7, for respectively locking the switch point in closed and open positions. In the travel of the friction roller 13 along the proximal portion 12 of the spiral groove 11 in the drum 10, the rock shaft 9 is turned 75 in switch throwing direction, and during the first portion of such travel the dog 25 is moved toward the block 30 and its shoulder 27 engages the end 34 of the lever 35 and forces the same back into the slot 31, thereby swinging said lever 35 and causing its finger 36 to swing and retract the locking device 38, whose finger 39 is withdrawn from the recess 40, allowing the switch bar to be moved in the final travel of the roller 13 80 along the portion 12 of the spiral groove to throw the switch point to open position. As the end 34 of the lever 35 recedes in the slot 31, the guide portion 28 of the dog 25 enters the slot 33 and the beveled end 26 of the dog 85 engages and rides up over the beveled surface 32 of the trip block 30, as shown in Fig. 12, whereby the dog is lifted out of the path of the lock releasing lever. The collar 22 of the shaft 19 carries a depending 90 crank arm 42 provided with a pin 43 movable in a slot 44 in a link bar 45 pivoted to one end of a switch throw bar 46 extending outwardly at one end beneath the rails 3 and 5 and suitably fastened to the rail 5 to actuate the switch point. The pin and slotted link forms a lost motion connection between the shaft 19 and throw bar 46, whereby the rock shaft is adapted to turn to a preliminary 95 degree to effect the retraction of the locking device before imparting positive motion to the throw bar 46 and shifting the switch to open position. The locking device 38 has an arm 47 carrying a hollow boss 48 in which is inclosed a coiled spring 49 acting on a 100 stud 50 slidably mounted in the boss and engaging a suitable fixed abutment 51, said spring acting to normally throw the locking device into locking position, whereby when the switch bar 7 is released and the switch is thrown, the finger 39 of the locking device will snap into the recess 41 and thereby 105 lock the switch in open position for travel of the rolling stock between the main and branch lines. When the roller 13 of the 110 115 120 125 130

actuating device 16 reaches the straight intermediate portion 14 of the spiral slot in the drum 10 a momentary pause in the motion of the drum, which has been fully thrown to switch opening position, takes place, whereby the locking device is permitted to move into the recess 41 while the bar 7 maintains an absolutely stationary position, after which the roller 15 traverses the distal portion 13 of the spiral groove in the switch throwing device 10 and returns said switch throwing device and the rock shaft 19 and its parts to normal position, thus resetting the switch throwing mechanism in the main line for subsequent action.

Arranged along the inner side of the branch rail 3 in proximity to the switch point is a laterally movable guard rail 52, acting also as a switch throwing and latch controlling device. This rail 52 is adapted to be moved away from the rail 3 by the flanges of the wheels of the rolling stock. The switch point is adapted to be always, except when positively thrown and locked in open position, moved to closed position by a coiled actuating spring 53 inclosed in a suitable casing 54 slidably receiving a stud 55 on the switch rail 5; while the guard rail 52 is normally held in contact with the rail 3 by suitably increased retracting springs 56. Extending longitudinally of the track at the switch point is an oscillatory rod 57 journaled in suitable bearings 58 and provided with crank arms 59 coupled to the guard rail 52 by connecting rods 60, whereby when the rail 52 is moved inwardly by the flange of a wheel the rod 57 will be rocked in a direction toward said guard rail. Adjustably secured to said rod by set screws 61 are collars 62 and 63, respectively carrying an actuating pin or arm 64 and a trip pin or arm 65. The arm 64 is movable in a slotted yoke 66 fixed to the rail 5 or throw bar 46 and is normally out of engagement with the inner end of the yoke, thus forming a lost motion switch throwing and retaining connection between the switch point and guard rail whereby independent motion of the bar 46 under the action of the switch throwing device in the main line is permitted without interference from the said switch throwing and retaining means in the branch line; the lost motion connection 42 and 45 between the throw bar 46 and crank shaft 19 similarly permitting actuation of said throw bar from the guard rail or switch throwing device in the branch line without interference from the switch throwing mechanism in the main line.

The pin 65 is arranged at an angle in advance of the pin 64 in the direction of actuating or controlling motion of the rod 57 and is adapted to engage an inclined or cam surface 67 on the latch 38 to trip said latch

to releasing position. When the guard rail is pressed away from the rail 3 and rocks the rod 57, the pin 65 engages and releases the latch in the manner described prior to the engagement of the pin 64 with the yoke 66. It will thus be understood that when the switch is thrown open for the travel of a vehicle from the main line to the branch line, the wheels of the vehicle will engage and move the guard rail to cause the latch to be released, the switch being held open until the vehicle fully enters the branch line and releases the guard rail, when the spring 53 and springs 56 will return the switch point and guard rail to normal position, thereby again closing the switch for travel on the main line, in which closed position the switch is automatically locked in the manner hereinbefore described. On the travel of a vehicle from the branch line to the main line, the switch point is automatically thrown to open position and maintained in such position by the wheels of the vehicle until such vehicle has fully entered the main line, when the switch point will again be automatically closed. In this operation it will be understood that the movement of the guard rail first releases the latch through the medium of the pin 65 and then effects the throw of the switch through the engagement of the pin 64 with the yoke 66, whereby switch opening movement is transmitted to the throw bar. When the guard rail is released the retracting springs return the parts to normal position as hereinbefore fully described. It will be observed that when the switch is thrown open from the main line it is locked in open position and afterward released by the action of the guard rail, whereas in the throwing of the switch to open position from the branch line the switch is held open and the latch held retracted by the guard rail until said rail is released, whereupon the switch is automatically closed and locked in closed position.

In order to permit the switch point to be manually operated, I provide an operating means comprising a hand lever 68 fulcrumed on a rod 69 and provided with a crank arm 70. The said arm 70 is provided with a trip pin 71 and is connected by a link 72 with a sliding and laterally movable trip bar 73 extending through a guide 74. The inner end of this bar 73 is provided with a contact pin or cam 75 normally spaced from and arranged in juxtaposition to a cam lug 76 on the adjacent end of the latch 38. The bar 73 is normally held rigidly pressed by a spring 77 against a wall of the guide 74 against lateral movement during the forward motion of the bar, whereby in such motion of the bar the cam projection 75 will engage and slide over the inclined face 78 of the latch and tilt the latch to retracted position.

position. When the cam 75 passes beyond the inclined face 78 it releases the cam 76 and moves into engagement with the curved face 79 of said cam 76, over which said cam 75 rides in the backward movement of the bar. In such backward travel of the bar, the bar is permitted to yield laterally by the spring 77 so that it will clear the lug 76 and return to normal position without interference from or injury to the latch. Connected with the switch rail 5 or bar 7 is a throw bar 80 provided with a pin or projection 81 which lies normally in advance of the pin 71 and in such position that the bar 73 in its travel will engage and retract the latch prior to the engagement of the pin 71 with the pin 81, through which the switch is thrown to open position by means of the hand lever. In other words, the distance between the parts 75 and 76 is less than the distance between the parts 71 and 81 so that in the operation of the hand switch lever the latch will first be retracted and the switch then thrown, the switch being locked in thrown position in the manner before described. The lever 68 is so weighted that when it is released by the switchman after the switch is thrown it will drop back automatically by gravity to normal position, thus resetting or withdrawing the manually controlled latch releasing and switch throwing mechanism back to normal position, so that it will not interfere with the operation of the automatic mechanism or with the subsequent release of the latch by the action of the guard rail and return of the switch to closed position. By this means all danger of the switch mechanism actuated by the hand lever being left in latch releasing position through negligence will be avoided. It will be observed that the parts 71 and 81 provide a lost motion connection between the hand switch lever and the bar 80 by which movement of said bar with the switch point is permitted for the independent throw of the switch by either of the automatic switch throwing devices and for the return of the switch to closed position without interference. The lever 68 is provided with a suitable locking device 82 adapted to automatically interlock with a stationary keeper 83 when the lever drops by gravity to normal position, thus insuring the positive and certain locking of said lever against surreptitious operation, it being understood that the lock may only be opened to free the lever for use by means of a prescribed type of key. A switch stand 84 of any suitable type may be arranged in proximity to the switch point and provided with any preferred type of signal target 85 operated through a suitable connection 86 with the throw bar 46.

It will be seen from the foregoing description that the invention provides a simple, reliable and efficient type of switch

mechanism in which the switch point is positively locked in open and closed position against liability of shifting, thus affording a safeguard against its accidental or malicious operation. It will also be seen that it provides a switch mechanism which is adapted to be positively and reliably operated by the rolling stock from either the main or the branch line, and also operated manually when occasion requires in an absolutely safe manner. It will further be seen that simplicity is secured by the use of a single locking mechanism for holding the switch point both open and closed, and by the provision of lost motion connections whereby the switch point may be independently operated and controlled by the respective sets of switch throwing devices. An important advantage is secured in the double use of the rail 52 as a guard rail and switch throwing and controlling device, as by means of this rail and the devices operated thereby a safe passage of the rolling stock over the switch in traveling from the main to the branch line, and vice versa, is afforded, while through the pressure of the flanges of the wheels of the rolling stock thereon the switch point is positively held open until it is cleared by all of the wheels, thus avoiding any liability of the premature closing of the switch.

In practice the latch device and related parts are preferably provided with a suitable cover or housing 87 to prevent them from being tampered with or injured by extraneous objects, as well as to prevent exposure thereof to the action of the elements. The bar 7 is also preferably coupled to the rail 6 by an elastic connection normally exerting pressure on the rail 6 to force it toward the rail 2 so that it will take up or compensate for any variation between the distance between the tracks caused by spreading or looseness of the connections from wear. This elastic connection is shown in the present instance in the form of a plunger or piston member 88 movable in a cylinder or casting 89 within which is arranged a coiled spring 90 normally maintained compressed or under tension to provide for the desired compensating or take-up action. If desired, the collar 22, instead of being fixed to the shaft 19, may be loosely mounted thereon and coupled by a coiled spring 91 with a fixed collar 92, as shown in Fig. 19, adjustably secured to the shaft by a set screw 93, whereby the spring may be tensioned to any desired degree. This spring forms a yielding connection between the shaft and the collar 22 which will allow the shaft to turn and transmit motion to the switch point when conditions are normal, but will prevent liability of damage to the switch mechanism in the event that the switch point should accidentally or mali-

ciously become choked or held from movement in any way.

I claim:—

1. In a railway switch mechanism, a self-closing switch point, a self-projected locking device for locking the switch point in open and closed positions, a train-operated switch-throwing and lock controlling device in the main line, said device being automatically thrown and returned to normal position by a passing train, lost-motion lock controlling means actuated on the first half of the switch-throwing motion of said switch-throwing device to retract the locking device and free it for a secondary locking action, a lost-motion connection between said switch-throwing device and the switch point operative on the final portion of the switch-throwing motion of said switch-throwing device to throw the unlocked switch point to open position, a train-controlled, spring retracted switch-throwing and lock controlling device in the branch line, a lost-motion connection between the same and the switch point co-acting with the first named lost-motion connection to permit the said switch-throwing and lock controlling devices to have independent switch-throwing and lock controlling actions, and means associated with said latter named lost-motion connection for engaging and retracting the locking device before the lost-motion connection is rendered effective and for holding the locking device retracted while said second named switch-throwing and lock controlling device is in thrown position.

2. In a railway switch mechanism, a self-closing switch point, a self-projected, spring actuated locking device for locking the switch point in open and closed positions, a train-operated switch-throwing and lock controlling device in the main line, said device being automatically thrown and returned to normal position by a passing train, lost-motion locking controlling means actuated on the first half of the switch-throwing motion of said switch-throwing device to retract the locking device and free it for a secondary locking action, a lost-motion connection between said switch-throwing device and the switch point operative on the final portion of the switch-throwing motion of said switch-throwing device to throw the unlocked switch point to open position, a train-controlled, spring retracted switch-throwing and lock controlling device in the branch line comprising a wheel-actuated guard rail, a rock shaft actuated by the said guard rail, a lost-motion connection between said shaft and the switch point co-acting with the first named lost-motion connection to permit the said switch-throwing and lock controlling devices to have independent switch-throwing and lock controlling actions, a projection carried by the locking device and having a cam surface, and a projection upon the rock shaft for engagement with said cam surface before the lost-motion connection is rendered effective for retracting the locking device and for holding said locking device retracted while said guard rail is in thrown position.

4. In a railway switch mechanism, a self-closing switch point, a self-projected, spring actuated locking device for locking the switch point in open and closed positions, a train-operated switch-throwing and lock controlling device in the main line, said device being automatically thrown and returned to normal position by a passing train and including a rock shaft, lost-motion lock controlling means actuated on the first half of the switch-throwing motion of said switch-throwing device to retract the locking device and free it for a secondary locking action, a lost-motion connection between said rock shaft and the switch point operative on the final portion of the switch-throwing motion of said rock shaft to throw the unlocked switch point to open position, a train-controlled, spring retracted switch-throwing and lock controlling device in the branch line, a lost-motion connection between the same and the switch point co-acting with the first named lost-motion connection to permit the said switch-throwing and lock controlling devices to have independent switch-controlling and lock controlling actions, said lost-motion connection including

a rock shaft, and means actuated by said shaft for engaging and retracting the locking device before the lost-motion connection is rendered effective and for holding the locking device retracted while said second named switch-throwing and lock controlling device is in thrown position.

3. In a railway switch mechanism, a self-closing switch point, a self-projected, spring actuated locking device for locking the switch point in open and closed positions, a train-operated switch-throwing and lock controlling device in the main line, said device being automatically thrown and returned to normal position by a passing train, lost-motion locking controlling means actuated on the first half of the switch-throwing motion of said switch-throwing device to retract the locking device and free it for a secondary locking action, a lost-motion connection between said switch-throwing device and the switch point operative on the final portion of the switch-throwing motion of said switch-throwing device to throw the unlocked switch point to open position, a train-controlled, spring actuated switch-throwing and lock controlling device in the branch line comprising a wheel-actuated guard rail, a rock shaft actuated by the said guard rail, a lost-motion connection between said shaft and the switch point co-acting with the first named lost-motion connection to permit the said switch-throwing and lock controlling devices to have independent switch-throwing and lock controlling actions, a projection carried by the locking device and having a cam surface, and a projection upon the rock shaft for engagement with said cam surface before the lost-motion connection is rendered effective for retracting the locking device and for holding said locking device retracted while said guard rail is in thrown position.

4. In a railway switch mechanism, a self-closing switch point, a self-projected, spring actuated locking device for locking the switch point in open and closed positions, a train-operated switch-throwing and lock controlling device in the main line, said device being automatically thrown and returned to normal position by a passing train and including a rock shaft, lost-motion lock controlling means actuated on the first half of the switch-throwing motion of said switch-throwing device to retract the locking device and free it for a secondary locking action, a lost-motion connection between said rock shaft and the switch point operative on the final portion of the switch-throwing motion of said rock shaft to throw the unlocked switch point to open position, a train-controlled, spring retracted switch-throwing and lock controlling device in the branch line, a lost-motion connection between the same and the switch point co-act-

ing with the first named lost-motion connection to permit the said switch-throwing and lock controlling devices to have independent switch-throwing and lock controlling actions, and means associated with said latter 5 named lost-motion connection for engaging and retracting the locking device before the lost-motion connection is rendered effective and for holding the locking device retracted 10 while said second named switch-throwing and lock controlling device is in thrown position.

5. In a railway switch mechanism, a self-closing switch point, a self-projected, spring 15 actuated locking device for locking the switch point in open and closed positions, a train-operated switch-throwing and lock controlling device in the main line, said device being automatically thrown and re 20 turned to normal position by a passing train and including a rock shaft, lost-motion lock controlling means actuated on the first half of the switch-throwing motion of said switch-throwing device to retract the 25 locking device and free it for a secondary locking action, a lost-motion connection between said rock shaft and the switch point operative on the final portion of the switch-throwing motion of said rock shaft to throw 30 the unlocked switch point to open position, a train-controlled, spring actuated switch-throwing and lock controlling device in the branch line comprising a wheel-actuated 35 guard rail, a rock shaft actuated by the said guard rail, a lost-motion connection between 40 said shaft and the switch point co-acting with the first named lost-motion connection to permit the said switch-throwing and lock controlling devices to have independent 45 switch-throwing and lock controlling actions, a projection carried by the locking device and having a cam surface, and a projection upon the second-named rock shaft for engagement with the said cam surface before the associated lost-motion connection 50 is rendered effective for retracting the locking device and for holding said locking device retracted while said guard rail is in thrown position.

5. In a railway switch mechanism, a self-closing switch point, a self-projected locking device for locking the switch point in open and closed positions, a train-operated switch-throwing and lock controlling device 55 in the main line, said device being automatically thrown and returned to normal position by a passing train, lost-motion lock controlling means actuated on the first half of the switch-throwing motion of said switch-throwing device to retract the locking device and free it for a secondary locking action, a lost-motion connection between said switch-throwing device and the switch point 60 operative on the final portion of the switch-throwing motion of said switch-throwing de-

vice to throw the unlocked switch point to open position, a train-controlled, spring retracted switch-throwing and lock controlling device in the branch line, a lost-motion connection between the same and the switch point co-acting with the first named lost-motion connection to permit the said switch-throwing and lock controlling devices to have independent switch-throwing and lock controlling actions, means associated with 70 said latter named lost-motion connection for engaging and retracting the locking device before the lost-motion connection is rendered effective and for holding the locking device retracted while said second named switch-throwing and lock controlling device is in thrown position, a hand-operated switch-throwing device having a lost-motion connection with the switch point, and means 75 operated thereby for releasing the locking device prior to the taking up of the lost-motion, holding the locking device retracted while the switch point is thrown and then releasing the locking device to permit it to lock the switch point in thrown position. 80

7. In a railway switch mechanism, a self-closing switch point, a self-projected locking device for automatically locking the switch point in open and closed positions, a train-operated and retracted switch-throwing and lock controlling device in the main line operative in the travel of rolling stock from the main to the branch line to first retract the locking device and then throw the switch and release the locking device to lock 90 the switch in thrown position, and train-controlled, self-retracting means in the branch line operative in the travel of rolling stock from the main to the branch line to retract the lock and release the switch for 95 subsequent closing movement while holding it from closing until the rolling stock passes into the branch line, said means being operative in the passage of rolling stock from the branch line to the main line to first retract the locking device and then throw the switch open and hold the locking device in retracted position, said means being freed for a self-retracting action on the passage 100 of the rolling stock into the main line and acting to release the locking device to permit the switch point to close and the locking device to lock it in closed position, the said switch-throwing and lock controlling device and means including lost-motion elements 105 permitting separate and independent operations thereof. 110

8. In a railway switch, a self-closing switch point, a plurality of devices for throwing said switch point, a single self-projected lock commonly and directly controlled by said switch-throwing devices, for locking the switch point in closed and opened positions, and means for permitting independent control of the locking device and 125 130

actuation of the switch point by each of said switch-throwing devices.

9. In a railway switch, a self-closing switch point, a plurality of devices for throwing said switch point, a single self-projected locking device commonly and directly controlled by said switch-throwing devices, for locking the switch point in closed and opened positions, and lost-motion elements in the respective switch-throwing devices for permitting independent control of the locking device and actuation of the switch point by each of said switch-throwing devices.

10. In a railway switch, a self-closing switch point, a single spring-projected locking device for holding the switch point in open and closed positions, a lock-releasing element, a switch-throwing device, an actuating element operated thereby for actuating said lock-releasing element after releasing said locking device to permit the switch to be thrown so as to adapt said locking device for automatic action to relock the switch in thrown position, and means for throwing said elements out of engagement.

11. In a railway switch, a self-closing switch point, a self-projected locking device for locking the switch point in open and closed positions, a pivoted releasing member therefor, a switch-throwing device including a rock shaft, an actuating member operated thereby to engage and move said releasing member, and means for throwing said actuating member out of the path of said releasing member upon the release of the switch, to free the locking device for movement to lock the switch in thrown position.

12. In a railway switch, a self-closing switch point comprising a pair of switch rails, a switch bar connecting said rails for movement in unison, said switch bar comprising relatively movable sections, a spring tending to normally spread said sections, a locking device to engage the bar to lock the switch point in open and closed positions, a wheel-controlled laterally movable spring-retracted switch-throwing rail connected with one of the switch bar sections, and means actuated thereby for controlling the locking device.

13. In a railway switch, an automatically closing switch point, a switch bar connected therewith, a pivoted spring projected latch adapted to lock said switch bar in switch opening and closing positions, a pivoted releasing lever having a controlling arm and a latch engaging arm, a switch throwing device including a rock shaft having a crank, and a latch releasing dog pivoted to said crank and provided with a shoulder to engage and operate the controlling arm of said releasing member and also provided with an abutment surface, and a combined guide and trip member engaged by said dog and adapt-

ed upon the actuation of said releasing member for contact with the abutment surface of the dog to deflect said dog upwardly out of the path of the controlling arm of the releasing member.

14. In a railway switch, an automatically closing switch point, a switch bar connected therewith, a pivoted spring projected latch for locking said switch bar in switch opening and closing positions, a pivoted releasing lever having a retracting arm engaging the latch and a controlling arm, a trip member forming a guide for said controlling arm and having a guide slot and an abutment surface, a switch throwing device including a rock shaft, a crank arm carried by said shaft, and a dog pivoted to said crank arm to slide horizontally and tilt vertically, said dog having a portion provided with a shoulder to engage the guide slot in the trip member and the controlling arm of the latch releasing member to actuate the latter, and an abutment surface adapted upon engagement with the abutment surface of the trip member to tilt said dog upwardly out of the path of the releasing member.

15. In a railway switch, an automatically closing switch point, an automatic lock for locking the switch point in open and closed positions, a switch bar connected with the switch point, a switch throwing device including a rock shaft having a preliminary and a final motion, means actuated by the preliminary motion of the shaft to release the lock for a secondary locking action, a lost-motion throw connection between the rock shaft and switch bar, operable on the final motion of the shaft to throw the switch, an automatically retractile wheel operated guard rail, a rock shaft actuated by said guard rail and having a preliminary and final motion, a lock releasing member on said shaft operated on its preliminary motion, and a lost-motion throw connection between said shaft and the switch bar for throwing the switch on the final motion of said shaft, said lost-motion connections and latch releasing devices controlled by the shafts being adapted to permit independent lock releasing and switch throwing actions on the movements of the switch throwing device and guard rail, respectively.

16. In a railway switch, an automatically closing switch point, a pivoted spring actuated locking device for locking said switch point in open and closed positions, said locking device having projecting arms, one of said arms having a pair of cam portions, a switch throwing device including a rock shaft having a lost-motion connection with the switch point, releasing mechanism operated in the initial portion of the motion of said shaft to engage the other arm of the locking device and adapted to successively

retract said locking device to unlock the switch and release said locking device to lock the thrown switch, a second switch throwing device having a lost-motion connection 5 with the switch point and provided with a projection to engage one of said cam surfaces on the locking device to first retract and then release the locking device, and a third switch throwing device having a lost- 10 motion connection with the switch point and provided with a projection to engage the second cam surface of the locking device to preliminarily retract and release the locking device, each switch throwing device and 15 co-acting lock controlling means being operable independently of the others.

17. In a railway switch, an automatically closing switch point, a spring projected locking device for locking the same in open and 20 closed positions, said locking device having a cam provided with opposite cam surfaces, a switch throwing device, a longitudinally and laterally movable member operated thereby, said member having a projection to 25 successively engage the cam surfaces of said projection and normally lying in a plane for engagement with one of said cam surfaces, a spring controlling said member and adapted to permit lateral motion thereof, and a connection between the switch throwing device and switch for throwing the switch upon the release of the locking device.

18. In a railway switch, an automatically closing switch point, a spring projected locking device for locking the same in open and closed positions, a switch throwing device, a member operated on the first portion of movement of the switch throwing device to engage and retract the locking device and 35 then to release the locking device, a bar connected with the switch point and having a projection, and a projection upon the switch throwing device operated on its final period of movement to engage the first named 40 projection and throw the switch.

19. In a railway switch, a self-closing, spring retracted switch point, a spring-projected locking device for locking the same in open and closed positions, a switch throwing and lock controlling device in the main 45

line operative to retract the locking means and throw the switch and release the locking means to adapt the same to lock the opened switch, a switch throwing and lock controlling device in the branch line operative on the passage of a train from the main line to the branch line to retract the locking means and hold the switch open and finally to free the switch for closing motion, and operative on the passage of a train from 55 the branch line to the main line to retract the locking means, throw the switch and hold it open and the locking means retracted and finally to release the switch and locking means for automatic switch closing and 60 locking actions, and lost-motion elements to permit said switch throwing and lock controlling devices to have independent action. 65

20. In a railway switch, a self-closing switch point, a self-projected locking device 70 for locking the same in open and closed positions, a device movable in opposite directions to trip and retract the locking device and release it for subsequent locking action, a lever manually movable to adjust said device in a direction to trip the latch and automatically movable back to normal position to adjust said device for the releasing action, lost-motion means actuated by the lever in its first-named movement to throw 75 the switch point after the retraction of the locking device and on the second-named movement of the lever to release the switch point for closing movement on the release of the locking device, and means for automatically locking said lever against movement on its return to normal position.

21. In a railway switch, an automatically closing switch point, a spring controlled expansion bar connecting the rails thereof, a 80 lock device for engagement with said bar to hold the switch in open and closed positions, and means for successively releasing the lock and throwing the switch.

In testimony whereof I affix my signature 85 in presence of two witnesses.

MARSHALL L. SHEPHERD.
